COMMERCIAL BUILDING

Joseph B. Schwartz, 278 W. 86th St., New York, N.Y.

Filed Mar. 30, 1962, Ser. No. 69,500

Term of patent 14 years

(Cl. D13—1)

FIG. 1

FIG. 2

A right elevational view similar to FIGURE 4 would be a mirror image of the view shown in FIGURE 4.

The dominant features of my design reside in the portions shown in full lines in the drawings.

I claim:

The ornamental design for a commercial building, substantially as shown and described.
